Primary Examiner — Derrick Holland*Assistant Examiner* — Lauren Calve(74) *Attorney, Agent, or Firm* — QuickPatents; Kevin Prince(57) **CLAIM**

I claim the ornamental design for an earring keeper, as shown and described.

DESCRIPTION

FIG. 1 is a front elevational view of an earring keeper showing my new design, the rear elevational view being a mirror image thereof;

FIG. 2 is a left-side elevational view of FIG. 1, the right-side elevational view being a mirror image thereof; and,

FIG. 3 is a top plan view of FIG. 1, the bottom plan view being a mirror image thereof.
